UNITED STATES PATENT OFFICE

BENJAMIN GILOWITZ, OF NEW YORK, N. Y.

COMPOSITE SHOE HEEL

Original application filed August 29, 1929, Serial No. 389,236. Divided and this application filed January 31, 1930. Serial No. 424,934.

The invention aims to provide a new and improved heel construction in which compressed paper, leather or the like, may be advantageously used in connection with some 5 yieldable or elastic material such as rubber.

A further object is to provide a yieldable tread member with spaced upstanding tongues formed integrally therewith and to provide a heel body with spaced grooves in 10 which the tongues are secured, the tread member and the heel body being tightly cemented or otherwise secured together.

With the foregoing in view, the invention resides in the novel subject matter hereinafter 15 described and claimed, description being accomplished by reference to the accompanying drawings.

Fig. 1 is a perspective view.

Figs. 2 and 3 are vertical sectional views on 20 lines 2—2 and 3—3 of Fig. 1.

In the drawings above briefly described, the preferred construction has been illustrated. This construction will be herein 25 rather specifically explained, with the understanding that within the scope of the invention as claimed, variations may be made.

The heel body 20 may be formed from leather, compressed paper or other desired material, the longitudinal and rear edge portions of said body being provided with spaced 30 vertical grooves 21 extending upwardly from the lower side of the body and preferably opening through the upper side thereof. These grooves are preferably parallel-sided and rather shallow.

Cemented, vulcanized or otherwise secured to the lower side of the body 20, is a yieldable lift or tread member 22 of rubber or the like, said tread member being provided with integral 40 upstanding tongues 23 which are snugly received in the grooves 21, said tongues being cemented, vulcanized or secured in the grooves in some other appropriate manner.

The construction above described affords a tenacious bond between the heel body and the tread member and also provides a heel of attractive appearance. When the tread member 45 22 has become badly worn, it may be cut from the tongues 23, leaving the latter

secured to the heel body 20. Then, a new rubber heel may be applied to said heel body and finished in the usual way. Instead of doing this, if so desired, the tread member 55 22 and the tongues 23 may be all removed from the body 20, and a new tread member having appropriate tongues may then be substituted. While the parts 20—22—23 are shown assembled as a single unit and may be marketed in this way, it will also be understood that the members 20 and 22, the latter with the tongues 23 and the former with the 60 grooves 21, may be marketed separately if desired.

By providing the novel construction shown 65 and described or a substantial equivalent thereof, a composite heel of simple and inexpensive, yet durable construction is provided, and one which will present an unusually attractive appearance, particularly on sport 70 shoes, it being obvious that the portions of the body 20 exposed at the edge of the heel, and the rubber portions 22 and 23, may be of distinguishing colors.

This application is a division of my parent 75 U. S. application, Serial No. 389,236, filed August 29, 1929.

I claim:—

1. A composite shoe heel comprising a heel body having a plurality of vertical grooves 80 in its edge extending upwardly from its lower side, a yieldable tread member secured against the lower side of said body, and vertical tongues integral with said tread member and secured in said grooves. 85

2. In a shoe heel, a heel body whose lower side is adapted to abut a lift, said body having circumferentially spaced grooves in its edge extending upwardly from its lower side, said grooves being adapted to receive up- 90 standing tongues on the lift.

3. In a shoe heel, a yieldable lift having up- 95 standing tongues integral with and rising from spaced portions of its longitudinal and rear edges, said tongues being adapted for reception in grooves of a heel body.

In testimony whereof I have hereunto affixed my signature.
